(57) **CLAIM**

The ornamental design for a watchband bottle opener, as shown and described.

DESCRIPTION

FIG. 1 is a perspective view of a watchband bottle opener positioned on the end of a watch band.

FIG. 2 is a perspective view similar to FIG. 1, but with the watch band buckled.

FIG. 3 is a perspective view similar to FIGS. 1 and 2, showing the watch band bottle opener opening the cap of a bottle.

FIG. 4 is a top plan view of the watch band bottle opener.

FIG. 5 is a bottom plan view of the watch band bottle opener.

FIG. 6 is a left side elevation view of the watch band bottle opener.

FIG. 7 is a right side elevation view of the watch band bottle opener.

FIG. 8 is a rear elevation view of the watch band bottle opener; and,

FIG. 9 is a front elevation view of the watch band bottle opener.

The broken lines depict environmental subject matter only and form no part of the claimed design.
